United States Patent Office.

ISAAC P. WENDELL, OF PHILADELPHIA, PENNSYLVANIA.

Letters Patent No. 60,809, dated January 1, 1867.

IMPROVEMENT IN MODE OF LUBRICATING JOURNALS.

The Schedule referred to in these Letters Patent and making part of the same.

TO ALL WHOM IT MAY CONCERN:

Be it known that I, ISAAC P. WENDELL, of the city and county of Philadelphia, and State of Pennsylvania, have invented a new and useful Improvement in Lubricating the Journals of Car and other Shafts; and I do hereby declare that the following is a full and exact description thereof, reference being had to the accompanying drawings, and to the letters of reference marked thereon.

The nature of my invention and improvement consists in a novel mode of supplying oil to the journals of car and other shafts, by creating a vacuum in a supply-box, substantially as follows. In the accompanying drawings—

Figure 1 is a plan or top view of the supply-box A, and parts attached to the same.

Figure 2 is a vertical cross-section of same, in combination with the journal E.

Like letters in both the figures indicate the same parts.

A is a box for containing the lubricating material; B is a cap plate of the box, that has a curved longitudinal groove, a, to which the oil is supplied to lubricate the journal, by means of spiral or twisted wires, C, arranged in the vertical tubes D, which project from the under side of said cap plate to within a short distance of the bottom of the box, so that the ends of the tubes shall always be in the oil. The lower ends of the wires C rest upon the bottom of the box, and the upper ends extend to the upper curved surface of the plate B, so as to keep said surface supplied with oil to lubricate the journal. The surface is kept up so as to have a gentle pressure against the journal, by means of springs under the supply-box, said springs resting upon the upper surface of the bottom of the journal box. As said arrangement of the springs with the boxes is fully shown in an application for a patent already granted to me, I deem a further description thereof unnecessary. There are small holes, b, in the cap plate B, to admit air in the box A, for the purpose I will presently describe.

The operation is as follows: As the journal E revolves, a vacuum is created in the tubes D, which causes the oil to ascend up the wires C to supply the journal, the oil spreading on the curved surface of the plate B, which gently touches the journal. The atmospheric air presses from without through the small openings, b, of the cap piece B, into the supply-box A, which gives an increased tendency of the oil to ascend the wires C, as it presses upon the upper surface of the oil within the box. This mode of lubricating journals may be frequently applied to the journals of mills and other shafts. It may, however, sometimes be found expedient to modify the arrangement. Instead of the spiral wires and tubes D, there may be a longitudinal slot in the cap piece B, which shall extend low enough into the box A to be always in communication with the oil, so that the latter may flow up the sides of the slot as a vacuum is created in the same. The wires C may be dispensed with by making the tubes small to easily form vacuums.

Having thus fully described my improvement in lubricating the journals of car and other shafts, what I claim therein as new, and desire to secure by Letters Patent, is—

An oil-box, A, having a tube D, in combination with plate B, (having orifices b b,) and journal E, substantially as described.

In testimony that the above is my invention, I have hereunto set my hand and affixed my seal this seventeenth day of July, 1866.
